UNITED STATES PATENT OFFICE

WILLIAM M. MYERS, OF DAYTON, OHIO

DESIGN FOR A REFRIGERATOR HINGE

Application filed December 15, 1930. Serial No. 37,997. Term of patent 7 years.

To all whom it may concern:

Be it known that I, WILLIAM M. MYERS, a citizen of the United States, residing at Dayton, Montgomery County, Ohio, have invented a new, original, and ornamental Design for a Refrigerator Hinge, of which the following is a specification, reference being had to the accompanying drawing, forming a part hereof.

The drawing is a perspective view of a hinge embodying my new design.

I claim:

The ornamental design for a refrigerator hinge substantially as shown.

In testimony whereof I have hereunto set my hand this 11 day of December, 1930.

WILLIAM M. MYERS.
